UNITED STATES PATENT OFFICE

2,523,980

REVOLVING DOOR

Frederick Carter Whiteford, Van Nuys, Calif.

Application March 23, 1948, Serial No. 16,505

10 Claims.

(Cl. 20—18)

1

This invention comprises novel and useful improvements in a revolving door and more specifically pertains to a revolving door and door casing which is collapsible in response to abnormal pressures such as created by a panic in a crowd of people passing therethrough, whereby the wings of the door are automatically folded, and additional openings are automatically provided in the door casing to permit rapid egress of the panicked people.

The principal object of this invention is to provide a revolving door which is collapsible in response to abnormal pressures of people passing therethrough, to increase the area of the door opening to a maximum for permitting very rapid passage of people therethrough.

An important feature of the invention resides in the provision of a revolving door having a plurality of wings extending radially from the axis of rotation of the door, accompanied by means for yieldingly holding the wings in assembled position to form a revolving door.

A further important feature of the invention resides in the provision of yieldable means for retaining the wings of the door in assembled position, which yieldable means will be automatically overcome by the imparting of an abnormal, predetermined force upon the wings of the door, to thereby fold the wings into a collapsed position occupying a minimum volume of space, and thus provide a maximum area of passageway through the door casing.

A still further feature of the invention comprehends the provision of a collapsible door as set forth in the preceding paragraphs, wherein a counterweight latch mechanism is provided for yieldingly holding the wings of the door in assembled position, and wherein a counterweight latching system is provided for retaining emergency doors in the door casing in their closed position.

And a final important feature of the invention to be specifically enumerated herein resides in the provision of a collapsible revolving door as set forth in the preceding paragraphs, wherein the entire weight of the revolving door assembly is supported by an overhead track carried by the door casing.

These, together with various ancillary features and objects of the invention which will later become apparent as the following description proceeds, are attained by this device, a preferred embodiment of which has been illustrated by way of example only in the accompanying drawings, wherein:

Figure 1 is a vertical transverse sectional view taken substantially upon the plane of the section line 1—1 of Figure 2, certain parts being broken away to show their construction in section and certain parts being shown in elevation;

Figure 2 is a top plan view of the revolving door

2

assembly and the door casing in their assembled position;

Figure 3 is a fragmentary vertical sectional view taken substantially upon the plane of the section line 3—3 of Figure 4, and illustrating certain positions of the parts when the door is in its collapsed position;

Figure 4 is a top plan view of the assembly, similar to Figure 2 but showing the emergency doors of the casing, and the position of the door latches and counterweights when the door is in its collapsed position;

Figure 5 is a fragmentary rear perspective view looking through the door casing and showing the parts in their collapsed position;

Figure 6 is a horizontal sectional view through the door casing below the plate 52 looking downwardly and showing the vanes of the revolving door in their collapsed position and the emergency doors of the casing open;

Figure 7 is a fragmentary vertical transverse sectional view taken substantially upon the plane of the section line 7—7 of Figure 2 and showing the door vane latching means and their counterweight mechanism, the vanes and latching mechanisms being indicated in the assembled position;

Figure 8 is a view similar to Figure 7 but taken substantially upon the plane of the section line 8—8 of Figure 4, and showing the parts in position for releasing the latching means for maintaining the vanes in their assembled position;

Figure 9 is a fragmentary vertical sectional view taken substantially upon the plane of the section line 9—9 of Figure 2, and showing in full lines the counterbalanced latching means for maintaining the emergency doors closed, and in dotted lines the position of the parts when the emergency doors are opened;

Figure 10 is a vertical transverse sectional detail view taken substantially upon the plane of the section line 10—10 of Figure 4 and illustrating the manner of supporting the rotary door upon the top of the door casing; and

Figure 11 is a fragmentary vertical sectional detail view taken substantially upon the plane of the section line 11—11 of Figure 10.

Referring now more specifically to the accompanying drawings wherein like numerals designate similar parts throughout the various views, attention is directed first to Figures 1 and 2, and also to Figures 4 and 6. In these figures, the numeral 10 designates a door casing formed by a cylindrical wall, which is provided with the customary service openings 12 and 14, see Figure 6. As will be readily understood, these openings provide the normal inlet and outlet means for persons entering or leaving a building or structure provided with the revolving door forming the subject of this invention. The casing wall 10 abutting the outlet opening 14 of the door casing is provided with hinged emergency door sections 16 which, in their closed position as indicated in dotted lines in Figure 6, form a con-

tinuation of the casing wall, but in their open position, indicated in full lines in Figure 6, increase the area of the outlet opening for a purpose to be later set forth.

A central stationary door post preferably of tubular steel construction, although any other suitable material and construction may be employed as desired, is indicated at 18 and is positioned axially or centrally of the door casing 10, and at its lower end is embedded in the floor or bottom surface 20 upon which the casing 10 rests. The post 18 constitutes the vertical axis about which the collapsible door, to be set forth hereinafter, is rotated, this door construction being supported upon the top of the door casing 10.

As indicated best in Figures 1 and 10, an annular plate 22 is supported upon the upper surface of the door casing 10 to constitute a trackway, for supporting the outer edges of the vanes of the rotary door, this plate having a peripheral upwardly extending flange 24 constituting a trackway for a purpose to be later set forth.

A plurality of door panels or vanes 26, 28, 30 and 32, four being chosen for purposes of illustrating the principles of the invention, although it will be understood that any suitable number may be employed as desired, are hinged at their upper and lower ends to the post 18 for individual and collective revolvable movement thereabout as set forth hereinafter. These door panels or vanes may be of any desired construction, except that at their upper and lower ends they are each provided with hinged plates 34 and 36, respectively, which are journaled upon the axle 18 in side by side relation. Conveniently, the upper edge and the upper side edges of the door panels are provided with a generally U-shaped metallic end plate 38 having its top portion bifurcated or channeled, as at 40, for receiving therein the upper hinged plate 34, and having its inner leg 42 positioned to form a journal bearing for rotatably supporting the door upon the post 18.

Adjacent its outer edge, each of the end plates 38 is provided with outer and inner upwardly extending parallel flanges and pins 44 and 46, respectively, the outer flange, as shown in Figure 1, being provided with laterally extending axles 48 upon which are journaled rollers 50 which ride upon the tracks 22 and support thereon the outer edges of the door panels.

An annular supporting cover 52, as shown best in Figure 1, overlies the top edges of the door panels or vanes, and extends within the pins 46 of the end plate 38, this supporting cover 52 being mounted by means of integral or rigidly attached U-shaped channel members 54 extending radially therefrom and provided with offset terminal portions 56 of similar construction, which overhang the casing 10. As shown in the detail view of Figure 10, these offset terminal portions 56 have journaled in their outer downturned end walls 58, and depending lugs 60 in the interior of the annular portions, a supporting axle 62, upon which is mounted a flanged supporting wheel 64 riding upon the upper edge of the track 24. By this means, the annular cover 52 is rotatably mounted upon the track on the top of the casing. At its center, the cover 52 is provided with an annular opening 66, see Figures 1 and 2, whose circumference is provided with a peripheral flange 70. The above mentioned upper hinges 34 are provided with upwardly extending brackets 72 whose upper ends are bifurcated, as at 74, and extend above the flange 70 and through the aperture 66. Journaled in the bracket 72 are

laterally disposed axles 76 carrying flanged supporting rollers 78 which rest upon the above mentioned flange 70, the latter constituting an annular supporting track for the inner ends of the door panels or vanes.

It will thus be seen that the rotating cover 52 is rotatably mounted and supported upon the outer annular track member 24, while the door vanes are rotatably supported at their outer end by the rollers 50 resting upon the annular track 22, and at their inner ends by the rollers 78 riding upon the track 70 on the inner periphery of the rotatable top 52.

It should be here noted that the door hinges 34 are provided with longitudinal slots 80, see Figure 6, to which the doors are slidably connected as by bolts 82 extending thru the bifurcated portion 40 of the end plate 38, and riding in these slots. The hinges 36 at the bottom of the panels are similarly constructed. By means of this slotted connection, the door panels may either be assembled radially of the door post 18, as shown in dotted lines in Figure 6, in which position the bolts 82 are at the innermost ends of the slots 80, or alternatively may be disposed in parallel relation as indicated in full lines in Figure 6, the slots accommodating this movement.

A latching means is provided for retaining the door panels in their assembled and radial position with respect to the axle of rotation, 18. This means comprises a plurality of latches 84, each having an offset terminal portion 87 pivoted as at 88 to the upper surface of the rotatable plate 52, this terminal portion 87 having an arcuate slot 88 in the outer end thereof, whereby the same may be selectively engaged with the upstanding pin 46 previously mentioned and carried by the outer end of the door panel end plate 38. Thus, when the latch 84 is in a radial position with the notch 88 engaging the pin 46, the door panel is secured to the rotatable cover in a radial position for rotation therewith. Obviously, to release the door panel and permit the same to be folded, it is merely necessary to oscillate the latch 84 about its pivot 88, thereby disengaging the notch 88 from the pin 46.

At its other end, the latch 84 is provided with a locking tongue 90 whereby the latch may be retained in its locking position.

Upon the radius extending to each of the pivot pins 88, there are secured pairs of L-shaped supporting brackets 92 and 94, the latter having radially inwardly extending parallel lugs 96. Fulcrumed between these lugs 96, as by a pin 98, are latch fingers 100 terminating at their inner ends in latching tongues 102 which are engageable in the above mentioned bifurcations 74 in the bracket 72, while the outer ends of the latches 100 extend through aligned slots 104 and 106 in the brackets 92 and 94, respectively, see Figure 1, and terminate in finger portions 108 which overlie and bear downwardly upon the above mentioned fingers 96 on the latches 84, which likewise extend through the slots 104. Journaled between the brackets 92 and 94, upon axles 110 and 112, see Figures 7 and 8, are a pair of bellcrank levers 114 and 116, having suitable counterweights 118 secured to the end of one arm, while the end of the other arm constitutes an abutment engaging opposite sides of the overlying tongue portions 96 and 108.

The arrangement is such that when the four door panels are in their radial positions, the

latches 84 will be radially arranged whereby the notches 88 will lock the pins 46, while simultaneously the latches 100 will engage the bifurcations 74 of the bracket 72 and lock both inner and outer edges of the door panels, in radial position relative to the axle 18, and supported by the revolvable cover plate 52. The two supporting latches are retained in their locked positions by the weighted bellcrank levers 114, as shown in Figure 7. In this position, the radial vane door assembly is now free to rotate about the axle 18, this rotation being assisted and facilitated by the supporting rollers 50 and 64, as well as by the rollers 78. When the door is rotated by normal pressure or force supplied to the door panels or vanes, this force will be resisted by the counterweights 118, through the leverage imparted by the bellcrank 116 and the mechanical advantages of the latch levers, and the assembly may be considered as rigid. However, when a more than normal force is applied to the door panels, as when a crowd under panicky conditions presses against one or more of the door panels, the counterweight linkage and latches which are adjusted for this purpose yield and permit the latches to be displaced about their pivots, whereby the door panels will fold or collapse into their collapsed position as shown in Figure 6.

However, since the collapsed door panels still occupy a considerable part of the cross sectional area of the doorway through the casing 10, a panic stricken crowd of people passing through the door opening will apply an inordinate force against the emergency door 16, thereby causing the latter to swing open against the predetermined resistance of the door closing bellcrank 120, fulcrumed as at 122 to supporting brackets 124 upon the upper portion of the door casing 10, see Figure 9, the outer end of the bellcrank being provided with suitable weights 126.

From the foregoing, the construction and operation of the device, together with its advantages, will now be evident, and further explanation is believed to be unnecessary.

However, it will be evident that numerous changes may be made within the principles of the invention after a consideration of the attached specification and the accompanying drawings, and accordingly it is not desired to limit the invention to the exact construction shown and described but all suitable modifications and equivalents may be resorted to falling within the scope of the appended claims.

Having described the invention, what is claimed as new is:

1. A foldable revolving door comprising a support plate, bearing means rotatably supporting said plate upon a door casing, a plurality of door panels, inner and outer support means for individually and adjustably supporting each panel from said plate and casing, respectively, hinge means for individually journaling each panel upon a door axle, inner and outer latch means for selectively securing the inner and outer support means to said plate radially of the axis of rotation of the door and retaining means engageable with said latches for securing the latter in latching position and yieldable to release said latches in response to the exertion of a predetermined force upon said door panels.

2. A foldable revolving door comprising a support plate, bearing means rotatably supporting said plate upon a door casing, a plurality of door panels, inner and outer support means for indi-

vidually and adjustably supporting each panel from said plate and casing, respectively, hinge means for individually journaling each panel upon a door axle, inner and outer latch means for selectively securing the inner and outer support means to said plate radially of the axis of rotation of the door and retaining means engageable with said latches for securing the latter in latching position and yieldable to release said latches in response to the exertion of a predetermined force upon said door panels, said support plate having supporting arms extending outwardly therefrom, said bearing means comprising rollers journaled at the outer extremities of the arms.

3. A foldable revolving door comprising a support plate, bearing means rotatably supporting said plate upon a door casing, a plurality of door panels, inner and outer support means for individually and adjustably supporting each panel from said plate and casing, respectively, hinge means for individually journaling each panel upon a door axle, inner and outer latch means for selectively securing the inner and outer support means to said plate radially of the axis of rotation of the door and retaining means engageable with said latches for securing the latter in latching position and yieldable to release said latches in response to the exertion of a predetermined force upon said door panels, said outer support means including a plate carried by each panel, said plate having a bearing for rotatable engagement with a door casing.

4. The combination of claim 3 wherein said plate has a latch finger, said outer latch means being selectively engageable with said finger.

5. The combination of claim 4 wherein said retaining means includes a lever having a portion for abutting said latch, said lever yieldingly resisting movement of said latch when engaged therewith.

6. The combination of claim 5 wherein said lever has a counterweight for yieldingly resisting movement of said latch when engaged therewith.

7. The combination of claim 3 wherein said plate has an opening, a latch finger carried by said hinge means and extending through said opening, anti-friction means carried by said finger and rotatably resting on said plate.

8. The combination of claim 7 wherein said plate has an annular track thereon surrounding said opening, said anti-friction means bearing upon said track.

9. The combination of claim 8 wherein said inner and outer latches are aligned in pairs, the adjacent ends of the aligned inner and outer latches having a common retaining means.

10. The combination of claim 9 wherein each of said retaining means comprises spaced brackets on said plate, aligned openings in said brackets for receiving said adjacent ends and counterweighted bellcranks journaled between said supports and engaging opposite sides of said adjacent ends.

FREDERICK CARTER WHITEFORD.
